(No Model.)

W. E. CRAM.
ELECTRICAL ANNUNCIATOR.

No. 447,558.

Patented Mar. 3, 1891.

UNITED STATES PATENT OFFICE.

WILLIAM E. CRAM, OF CAMBRIDGE, ASSIGNOR OF ONE-HALF TO EDWIN S. BECKFORD, OF QUINCY, MASSACHUSETTS.

ELECTRICAL ANNUNCIATOR.

SPECIFICATION forming part of Letters Patent No. 447,558, dated March 3, 1891.

Application filed May 23, 1890. Serial No. 352,820. (No model.)

To all whom it may concern:

Be it known that I, WILLIAM E. CRAM, of Cambridge, in the county of Middlesex and State of Massachusetts, have invented certain new and useful Improvements in Electrical Annunciators, of which the following is a specification.

It is the object of my invention to provide such improvements in electrical annunciators as will permit of the operation of the same with a low degree of energy as compared with that heretofore employed, and at the same time insure the retention of the raised "drops" against displacement by jarring and other effects attendant upon many devices upon which annunciators are used, as, for instance, upon elevators and steamboats.

It is also the object of the invention to provide an annunciator which shall be of shallow construction—that is, of a form or construction which shall occupy a minimum amount of space.

It is also the object of my invention to provide such improvements in annunciators as will simplify their construction and increase their usefulness and efficiency, all as is hereinafter more fully described and claimed.

Reference is to be had to the annexed drawings and to the letters of reference marked thereon, forming a part of this specification, the same letters designating the same parts or features, as the case may be, wherever they occur.

Of the drawings, Figure 1 is a front view of my improved annunciator incased. Fig. 2 is a similar view of the invention, the front of the casing being removed, and the circuit-wires connecting with the electro-magnets being omitted. Fig. 3 is a front view of a drop and its adjuncts, showing also a modification. Fig. 4 is a sectional plan of Fig. 3, taken on the line 4 4 of said figure. Fig. 5 is a side or end view of Fig. 4, the modified part being omitted.

In carrying out my invention as many annunciator-drops and actuating mechanisms therefor as may be required for the case in hand are used, constructing each of the said devices by providing a frame *a*, consisting of a piece of brass or other suitable material ca-

pable of being secured to the back board or plate *b* of the casing, and having angular projecting parts *c* *c'*, which support vertical guide-rods *d* for guiding the drop *e* in its movements. The drop *e* consists of a plate having ears *f* *f'*, provided with holes through which the rods *d* pass.

g designates an electro-magnet, the armature *h* of which is arranged to normally engage an extension *i*, connected with the ear *f'* of the drop *e*, and support the said drop in a raised position, the said armature being pressed away from the pole of the magnet by a light spring *j*.

The armature *h* is provided with an angular base part *k*, which normally rests upon the lower end of the spring *j*, the latter extending between the said base part *k* and the base *l* of the support for the electro-magnet *g*. The armature is also provided with inwardly-extending ears *m*, by means of which it is pivoted to ears *n*, extending upwardly from the sides of the base part *l*.

When the magnet is energized, as it may be by closing an electric circuit connected with the electro-magnet *g*, it overcomes the stress of spring *j* and is drawn into contact with the adjacent pole of the electro-magnet, and so drawing the said armature away from the extension *i* of the drop *e*, permitting the latter to fall to the lower ends of the guide-rods *d*. After the circuit is broken the spring *j* will press the armature *h* back to its normal position, when the drop *e* may be raised until the extension-piece *i* passes the upper end of the armature (pressing it slightly inward in so doing) and dropping back rests again upon the same, all as will be readily understood by an inspection of the drawings.

As many of the devices constructed as aforesaid as may be needed are properly secured in place upon a base-board *b* in such manner that the electro-magnets *g* will extend longitudinally toward the sides of the base-board and so that the slide-rods *d* will be in a vertical position.

Various means may be provided for raising the drops. As herein shown, I have provided a vertically-sliding frame having rods *o*, provided with laterally-projecting pins *p*, 100

adapted to engage the lowered or fallen drops *e* and raise the same until the projecting pieces *i* pass above the upper end of the pivoted armatures *h*, when the said sliding frame may 5 be lowered by gravity.

The spring *j* may be constructed of brass or other non-magnetic material, so as to insulate the armature *h* from the base *l* and prevent a magnetization of the latter.

10 If desired, the armature *h* may be provided with a laterally-projecting screw-threaded rod *q*, Fig. 3, upon which is arranged a weighted nut, so that the latter may be adjusted nearer to or farther from the armature, in accordance with the force with which it is desired 15 to hold the armature away from the adjacent pole of the electro-magnet.

The spring *j* is connected by means of solder or in other suitable way with the armature *h* at the angular point *z*, so that the weight *r*, when adjusted outward on the rod *q*, acts upon the spring, through the medium of the armature, to press the latter away from the core or pole of the electro-magnet, and 20 when the said weight is adjusted inward it acts upon the spring in a contrary way. The degree of force with which the armature is pressed away from the core corresponds with the hold of the armature upon the extension 25 of the drop and the degree of tension required to attract the armature to the core.

By arranging the electro-magnets so that the same may extend horizontally and longitudinally toward the sides of the base-board 30 a minimum amount of space is occupied.

It is to be observed that though the armature is delicately poised or pivoted, so that it may be attracted to the pole of the electro-magnet by the expenditure of light energy, 35 the said armature supports the drop very securely, so that ordinary jarring and vibrations of the frame, such as it would be subject to on a steamship or elevator, will not displace the drop. It is also to be noted that 40 the several parts of each device, aside from the electro-magnet, which is of common construction, can be easily and cheaply manufactured, so that the annunciator can be constructed at quite low cost.

It is obvious that changes may be made in 50 the form and arrangement of parts comprising my invention without departing from the nature or spirit thereof.

Having thus described the nature of my invention and explained a way of constructing 55 and using the same, I declare that what I claim is—

1. An annunciator comprising in its construction a plurality of electro-magnets extending horizontally and longitudinally toward the sides of their base-board, pivoted armatures at the ends of the said electro-magnets having their axes perpendicular to the cores of said electro-magnets, gravity-drops arranged in a plane parallel to the cores of said 60 magnets and provided with extensions to engage the upper end of the armatures when the latter are in their normal position, slide-rods for guiding the drops in their movements, and a lifting-rod for said drops, as set forth. 70

2. In an annunciator, the combination, with a series of gravity-drops provided with extensions, of the electro-magnets having each an armature pivoted at one end thereof and a spring interposed between the armature and the base of the electro-magnet and connected to said armature, substantially as set forth, 75 said extensions of the gravity-drops being designed to engage the upper ends of said armatures when the latter are in their normal 80 position, as stated.

3. The combination, with the frame *a*, having angular projecting parts *c c'*, of the electro-magnet, its support *l*, provided with ears *n*, the armature *h*, having the ears *m* pivoted 85 to the ears *n*, the guide-rods *d*, and drop *e*, provided with the extension *i*, as set forth.

In testimony whereof I have signed my name to this specification, in the presence of two subscribing witnesses, this 20th day of 90 May, A. D. 1890.

WILLIAM E. CRAM.
